[57] CLAIM

The ornamental design for a game card holding board with masking tabs, as shown and described.

DESCRIPTION

FIG. 1 is a top, front and left side perspective view of a Game Card Holding Board with Masking Tabs, showing my new design;

FIG. 2 is a perspective view of FIG. 1, with the masking tabs bearing portion shown in a partly open position;

FIG. 3 is a top plan view of my new design;

FIG. 4 is a left side view thereof;

FIG. 5 is a back view thereof;

FIG. 6 is a front view thereof; and,

FIG. 7 is an enlarged perspective view of a masking tab as seen in detail 7 in FIG. 1.
